(57) **CLAIM**

The ornamental design for a rock hold cap set, as shown and described.

DESCRIPTION

FIG. 1 is a front perspective view of a rock hold cap set in place on a rock hold, showing the design;

FIG. 2 is a left side view of FIG. 1;

FIG. 3 is a right side view of FIG. 1;

FIG. 4 is a front view of FIG. 1;

FIG. 5 is a back view of FIG. 1;

FIG. 6 is a top view of FIG. 1;

FIG. 7 is a bottom view of FIG. 1;

FIG. 8 is a front perspective view of a rock hold cap set floating next to their place on the rock hold of FIG. 1;

FIG. 9 is a left side view of FIG. 8;

FIG. 10 is a right side view of FIG. 8;

FIG. 11 is a front view of FIG. 8;

FIG. 12 is a back view of FIG. 8;

FIG. 13 is a top view of FIG. 8; and,

FIG. 14 is a bottom view of FIG. 8.

The broken lines in the drawings illustrate portions of the rock hold cap set which form no part of the claimed design.
